SIGNORS TO PACENT ELECTRIC COMPANY, INC., OF NEW YORK, N. Y., A CORPORATION
OF NEW YORK

DEVICE FOR CONVERTING ENERGY

Application filed April 9, 1930. Serial No. 442,973.

This invention relates to devices for converting mechanical vibrations into electrical impulses or vice versa and special objects of the invention are to provide a device of 5 this nature, which will be simple and effective and which may be readily manufactured at relatively low cost.

Various other objects and the novel features of the invention by which the attainment of such objects is effected will all appear as the specification proceeds.

The drawings accompanying and forming part of this specification illustrates one simple commercial embodiment of the invention, 15 but as this illustration is primarily for purposes of disclosure, it will be understood that the structure may be modified and changed without departure from the true spirit and broad scope of the invention.

Fig. 1 is a broken part sectional view of 20 a form of the invention embodied as a pickup for electric phonographs; Fig. 2 is a cross-sectional view as taken on substantially the plane of line 2—2 of Fig. 1; Fig. 3 is 25 a broken elevation of the device and Fig. 4 is an enlarged sectional detail of the same.

A constant magnetic field is provided in 30 the disclosure by a permanent U-magnet 5. This magnet is equipped with special pole pieces, one of them 6, of general C-shape with a gap 7 and the other 8 of U-form and disposed centrally within the C-shaped pole, substantially at right angles thereto. These 35 pole pieces 6 and 8 are carried by flat bars or back pieces 9, 10, secured flat to one face of the magnet by the through bolts 11, 12.

Mounted for cooperation with the double 40 pole piece 8 is an armature 13 disposed with its longitudinal axis substantially parallel with and intermediate the tips of this pole piece and this armature is shown as having a downwardly inclined needle holder 14 to receive the needle 15 and provided with a suitable needle clamping screw 16.

Windings 17, are shown engaged on the 45 two legs or sides of the U-shaped pole piece, said windings having suitable terminals 18 for connection of external circuit conductors.

The armature is movably supported in the 50 present disclosure by being secured on the

outer face of a flexible diaphragm 19. The action of this diaphragm and hence of the armature is "damped" and controlled in the present disclosure by a body of oil or other suitable damping liquid or fluid 20 confined in a cup or case 21, mounted between the sides of the U-magnet and encompassing the pole pieces and the coils. In the present illustration, the mounting of this case is effected by having the bases 9, 10, of the pole pieces 55 extending through opposite sides of the case and suitably secured thereto as by brazing or soldering, so that the projecting portions serve in effect as attaching or mounting brackets on the outside of the case. 60

The flexible diaphragm which mounts the armature is utilized as an end closure for the case, it being shown as removably secured thereto by the screw ring 22, the joint being made liquid tight by a suitable gasket 23. 65

The structure described may be encased between cheek plates 24, shaped and flanged to fit about the magnet, pole pieces and coil case, as indicated in Figs. 1 and 3, these cheek plates being shown as secured in place by the through bolts 11, 12 and by an extra clamp bolt 25 passed through the arch of the magnet. These same cheek plates are utilized in the present illustration to mount the unit on the end of the phonograph arm, the latter being indicated at 26 as clamped between the neck extensions 27 at one side of the cheek plates by a clamp screw 28. 70

The particular unit shown is designed for 75 operation with the lateral cut type of phonograph record, the armature and stylus holder being therefore positioned, so that lateral variations in the groove will rock the armature to vary the flux threading the coils and thereby set up variations in the coil circuit corresponding in sense to the mechanical movements of the stylus. The liquid bearing against the back of the diaphragm exerts a damping and controlling effect holding the armature within the proper limits of action 80 and preventing distortion effects. The liquid is of a nature to protect the coils and internal connections of the unit. The case, pole pieces and windings may be made up in final shape 85 before being attached to the magnet and the 90

100

mounting of the magnet merely requires the relative location of the parts and then the engagement of the bolts 11, 12 and 25 through the shell or cheek plates and enclosed parts. 5 The cheek plates are indicated as cut with circular openings 29 fitting about and bracing the coil case at both sides of the magnet, Fig. 2, so as to hold the same in rigidly braced relation. The liquid in the coil case has a 10 steady effect, enabling the needle to accurately follow the sound groove and the liquid in the case may be readily renewed, replaced, reduced or increased upon simply unscrewing the end ring which holds the diaphragm in 15 place. This mounting also permits the diaphragm to be rotated one way or the other, to vary the position of the armature and stylus holder. In this connection, also it will be noted that the U-shaped pole piece is 20 adjustably secured to its supporting bar 10 by a screw 30 extending through the back of the U-piece, so that this double pole piece and the windings carried thereby may be set at different angles in assembling or adjusting the 25 device. The diaphragm damping and coil containing case occupies a position transversely between the sides of the U-magnet, so as not to add too much to the bulk of the device, and it is well braced at both faces of 30 the magnet, so as not to shake loose or vibrate.

Figs. 3 and 4 illustrate a special form of diaphragm which is corrugated at 31 to provide the hinging axis indicated by the broken line 32 to facilitate flexure of the diaphragm along such axis. The diaphragm may be provided with additional corrugations at 33 at opposite sides of and parallel with the hinging corrugation at 31. In this way, flexure of the diaphragm on the proper axis is obtained without using the armature 13a as a stiffening member.

The stylus holder extends substantially at a right angle to or transversely of the axis 45 of flexure defined by the diametrically extending portion of different cross-section and the other portion or portions of different cross-section parallel to the axis and at one or both sides of the same aid in the flexure 50 of the diaphragm along this definite axis.

What is claimed is:

1. A device for conversion of mechanical and electrical impulses, comprising a U-magnet, a case secured transversely between the 55 sides within the arch of said magnet, pole pieces for said magnet located within said case, a winding associated with one of said pole pieces, a flexible diaphragm at one end of said case and an armature member carried 60 by said flexible diaphragm in cooperative relation to one of the pole pieces.

2. In a device of the character disclosed, a U-magnet provided with pole pieces, a case containing a damping liquid located within 65 the arch of the U-magnet and enclosing said

pole pieces, a flexible diaphragm sealing one end of the case and a member supported by said flexible diaphragm in cooperative relation to the enclosed pole pieces.

3. In a device of the character disclosed, 70 a U-magnet provided with pole pieces, a case containing a damping liquid located within the arch of the U-magnet and enclosing said pole pieces, a flexible diaphragm sealing one end of the case, a member supported by said flexible diaphragm in cooperative relation to the enclosed pole pieces, said cooperating member consisting of an armature and a winding supported in the case in position to be electrically effected by said armature. 75

4. In combination with a support, a U- 80 magnet, pole pieces for the arms of said magnet, a relatively movable member for cooperative reaction with said pole pieces, a mount for said member and clamp means for securing said mount, pole pieces, magnet and support all in assembled relation including cheek plates engaged with opposite faces of the pole pieces, magnet and support. 85

5. In combination with a support, a U- 90 magnet, pole pieces for the arms of said magnet, a relatively movable member for cooperative reaction with said pole pieces, a mount for said member and clamp means for securing said mount, pole pieces, magnet and support all in assembled relation including cheek plates engaged with opposite faces of the pole pieces, magnet and support, said mount including a case surrounded at least in part 95 by the magnet, the cheek plates being recessed to accommodate said case. 100

6. A device of the character disclosed, comprising a U-magnet, a case for containing a damping fluid, pole pieces connected with said case and having base portions projecting out of the case and by which said pole pieces and case are secured to the magnet, a flexible diaphragm closing one end of the case and a vibrating member carried by the diaphragm in cooperative relation to the pole. 110

7. In apparatus of the character disclosed, a diaphragm having a substantially diametrically extending corrugation defining a substantially diametrically extending axis of 115 flexure and a stylus holder connected with said diaphragm transversely of said axis of flexure.

8. In apparatus of the character disclosed, a diaphragm having a substantially diametrically extending corrugation defining a substantially diametrically extending axis of flexure and a stylus holder connection with said diaphragm transversely of said axis of flexure, said diaphragm having an additional 120 corrugation therein substantially parallel to and alongside said first corrugation. 125

9. In a device of the character disclosed, a diaphragm having formed therein a substantially diametrically extending portion 130

of different cross-section from other portions of the diaphragm and defining a substantially diametrically extending axis of flexure and a stylus holder connection with said diaphragm and disposed at an angle to said axis of flexure.

10. In a device of the character disclosed, a diaphragm having formed therein a substantially diametrically extending portion of
10 different cross-section from other portions of the diaphragm and defining a substantially diametrically extending axis of flexure and a stylus holder connection with said diaphragm and disposed at an angle to said axis
15 of flexure, said diaphragm having another portion of different cross-section alongside said first portion aiding flexure of the diaphragm along the axis aforesaid.

In testimony whereof we affix our signatures.
